CLAIM

The ornamental design for a ski shoe as shown and described.

DESCRIPTION

1. Ski shoe

1.1: Back, right perspective view, closed

1.2: Back, left perspective view, closed

1.3: Front, right perspective view, open

1.4: Left view, closed

1.5: Right view, closed

1.6: Top view, closed

1.7: Back view, closed

1.8: Top view, open

1.9: Bottom view, closed

1.10: Front view, closed

1.11: Front, right perspective view, closed

1.12: Front, left perspective view, closed

The broken lines and the area they surround show portions of the ski shoe that form no part of the claimed design.

1 Claim, 12 Drawing Sheets
